DEVELOPING HEAD FOR PHOTOLITHOGRAPHIC PLATE TREATING MACHINES

Harry A. Coughlin, St. Louis, Mo., assignor to
 John S. Swift Co., Inc., St. Louis, Mo., a corporation of Missouri

Application April 28, 1951, Serial No. 223,620

5 Claims. (Cl. 95—89)

1

This invention relates to improvements in developing heads for photolithographic plate treating machines, the present improvements more particularly relating to a developing head assembly which constitutes a continuation-in-part of the prior application of Harry A. Coughlin, Serial No. 718,063, filed December 23, 1946, now Patent No. 2,555,874.

The above mentioned prior application describes the manufacture of photolithographic printing press plates in great detail. As there described, the manufacturing procedure included the steps of coating a zinc plate with a solution of albumen and ammonium bichromate, which is sensitive to light when dry, reproducing from a photolithographic negative the matter to be printed on the light sensitized plate and developing the sensitized plate to bring out the exposed light hardened portions whereby to fix the image of the photolithographic negative in the sensitized zinc plate.

In developing the exposed photolithographic press plates, the present practice is to pour a developing ink onto the sensitized coating, then spread the ink over said coating with a towel and then rub down the inked surface with a second towel to absorb the surplus ink and to dry the remaining ink. The inked plate is then placed in a pan of water or under a tap and the inked coating hand-rubbed with a large ball of cotton to soften and wash away the soft non-printing areas, leaving the hard printing areas affixed to said plate.

This hand-inking and washing of the photolithographic press plate is a slow and arduous operation, requires a large stock of rubbing towels and cotton and results in the loss of all of the developing ink absorbed by the towels. Another objection is that the hands become stained with ink dyes, which are difficult to remove, inhalation of the chemical fumes causes sickness and loss of time; and physical contact with the ammonium bichromate causes serious poisonous infections which are difficult to cure and cause some employees to seek new occupations.

It is an object of the present invention to provide an improved developing head which will replace the hand rubbing operations with means which will mechanically and uniformly rub over the entire surface of the plate to be developed, thereby avoiding the difficulties mentioned above.

It is a further object of this invention to provide a plate developing head with a wrap-around fabric blanket of a material which will

2

imitate or reproduce the gentleness of touch obtained by hand operations, and positively maintain that touch uniformly over the entire surface of the plate during the developing procedure.

It is a further object hereof to utilize a pile fabric of wool cut plush with a tightly woven warp and weft to form a firm ground texture, such pile fabric constituting the wrap-around blanket carried by the developing head.

A further object of the present invention is to provide a hollow developing head having a water inlet and a plurality of water outlet ports arranged to direct the outgoing water against the wrap-around blanket carried by the developing head, thereby applying the pressure of the water against the wrap-around blanket to distend the same in such manner as to reproduce the gentle touch obtained in the hand operation.

A still further object of the present invention is to provide mechanical operating means for moving the developing head uniformly over the surface of a photolithographic plate to be developed, and to provide the developing head with means for permitting placement of the wrap-around blanket on the developing head without disturbing the position of the head relative to the photolithographic plate.

The invention consists in a hollow developing head operatively supported in a photolithographic developing machine, by means of power operated devices which cause the head to move in a predetermined orbit over the plates, and a pile fabric of wool cut plush positioned on the head so that the flow of the water supplied to the developing head for delivery to the photolithographic plate will distend the fabric and cause the pile filaments yieldingly to contact the surface of the plate to substantially reproduce or imitate the touch or contact pressure obtained in hand operations.

The invention further consists in the parts and in the combination and arrangement of such parts, as will hereinafter be described in connection with the accompanying drawings, wherein:

Fig. 1 is a fragmentary top plan view of the photolithographic plate treating machine disclosing the parts thereof adjacent the developing head;

Fig. 2 is a greatly enlarged transverse sectional elevational view taken along line 2—2 in Fig. 1;

Fig. 3 is an enlarged top plan view of the improved developing head;

Fig. 4 is a sectional view at line 4—4 in Fig. 2; Fig. 5 is a sectional view at line 5—5 in Fig. 2; Fig. 6 is a sectional view at line 6—6 in Fig. 2; Fig. 7 is a sectional view at line 7—7 in Fig. 2; and

Fig. 8 is a sectional elevational view of the plate rubbing blanket removed from the developing head body to show the means for securing the same to the body.

The automatic photolithographic plate treating machine of the above mentioned prior application, Serial No. 718,063, comprised a table having spaced stations for receiving, inking, heating and developing each plate. Only a fragmentary part of the machine has been shown in Fig. 1, wherein in the table it includes the heating and developing stations C and D. The heating station C is provided with an endless belt 13 having a power driven roll 15, and the belt cooperates with cross feed rolls 16 at the sides thereof. The station C also includes a battery of overhead infra-red electric head lamps 17 in a frame 17a above the belt 13.

The developing station D (Fig. 1) includes a stationary top panel 18 for supporting a plate (not shown), a pair of water spray pipes 19 disposed over said panel 18 at the plate receiving end, and a horizontally movable developing head 20 which engages the upper surface of the plate. The pipes 19 are connected with a water supply line 21, and the developing head 20 is connected to the same line 21 by a flexible hose 21a. The line 21 has an electrically operated cut-off valve 22 and a hand valve 23. The developing head 20 is shown more fully in connection with Figs. 2 and 5, wherein the head comprises a hollow box assembly having a top wall 25 provided with a water inlet nipple 26 for the hose 21a, a bottom wall 27 forming a broad, flat face provided with a plurality of water outlet ports 28, end plates 29, side plates 30 and intermediate transversely directed rib members 31 located adjacent the water inlet nipple 26. Each of said ribs is provided with enlarged openings 32 to permit free flow of the water from the zone immediately adjacent the inlet nipple toward each end of the hollow box or head.

The hollow head 20 (Figs. 2 and 5) is provided on its upper wall 25 with stirrup members 34 adjacent its opposite ends, each stirrup having outwardly extended foot elements 35 attached to the wall 25 and upwardly extending guide elements 36 connected at their outer ends by a bridge 37. The bridge 37 is provided with a threaded opening 38 in which is mounted an adjustment screw 39. In the vicinity of the water inlet nipple 26, the wall 25 is provided with a pair of spaced angular guide elements 40 which supplement the function of the guide portions 36 of the stirrups 34.

The hollow head 20 is operatively carried on a cross bar 42 (Figs. 1, 2 and 3) of the photolithographic treating machine. Cross bar 42 is provided with pairs of edge notches 43 (Figs. 5 and 7) which engage the guide portions 36 of the stirrups 34. An additional pair of edge notches 44 cooperate with the spaced guide elements 40. The notches in the cross bar 42 loosely engage the respective guides carried on the wall 25 of the hollow head which permits a relative rocking movement or play between the head and the cross bar in the direction defined by the guide portions 36 of the stirrups 34, whereby the hollow head is prevented from binding in or between these guide portions. Regulation of this relative rocking motion of the hollow head is obtained by providing the cross bar 42 with a pair of transverse mem-

bers 45 (Figs. 4 and 6) having their opposite end portions extending to each side of the cross bar to overlie the top surface of the wall 25. Each of the members 45 is provided with a threaded aperture to receive a leveling screw 46, there being two such leveling screws 46 for each member 45. The members 45 are connected with the bar 42 by means 47 of known type.

The hollow head 20 is provided with a wrap-around blanket B (Fig. 8) which is of a size to cover the lower or broad flat surface of wall 27 and provide sufficient material at its lengthwise margins to permit the blanket B to be wrapped around the opposite longitudinal sides of the head 20. Each longitudinal margin of the blanket B is clamped between a holder bar 50 and a backing bar 51, the bars being secured in clamp relation on opposite sides of the blanket B by means of a plurality of threaded elements 52 recessed in the bar 50. The holder bar 50 is provided with a pair of longitudinally spaced notches 53, each notch being adapted to engage with a fixed pin 54 projecting from the outer surface of the wall 25 for that purpose.

In mounting the wrap-around blanket B on the head 20, one of the holder bars 50 is first positioned with its notches 53 engaged over the pins 54, the blanket is then disposed about the lower wall 27 of the head, and the opposite holder bar 50 is then brought into position whereby its notches 53 engage the pins 54 provided therefor. In this manner, the pile 55 of the fabric B naturally assumes an erect position projecting normal to the broad flat face of the wall 27, so that the tip portions of the erect filaments constitute the portions of the blanket which rub the surface of the photolithographic plate which is to be developed and are receptive to the ink on such plates.

In use, the hollow head 20 is supplied with water through the flexible hose 21a under a low pressure condition. In one commercial machine, water was supplied to the machine at about 55 to 60 pounds per square inch, gauge. The valve 23 was turned toward closed position until the pressure in the head 20 was approximately one pound or less. This low pressure resulted due to the large volume of the head 20 compared to the one-half inch hose 21a, and the back pressure effect produced by the tightly woven warp and weft of the blanket B. Thus, the dynamic pressure effect of the flowing liquid caused the blanket to belly outwardly or assume a distended and somewhat curved position relative to the flat surface of wall 27 so that the erect filaments of the pile 55 in the central longitudinal zone of the blanket B moved away from the wall and was yieldingly held by the flow of the water. This action effectively reproduces or imitates the gentleness of touch which can be achieved by hand developing operations, but which is very difficult to maintain uniform.

It is preferred, in connection with the wrap-around blanket B, to employ a pile fabric of wool cut plush with a tightly woven warp and weft to form a firm ground texture which will offer a desired degree of resistance to the free flow of the water through the interstices of the warp and weft. The plate to be developed passes adjacent the erect filaments so that their tip portions become effective to reproduce a gentle but uniform rubbing touch on the surface of the plate to be developed and the blanket is more receptive to the ink. This use of a pile fabric of wool cut plush prevents an undesirable hard or hard

rubbing or scrubbing action on the photolithographic plate surface, so that the mechanical movement of the hollow head produces a uniformly gentle rubbing action over the full surface of the photolithographic plate and leads to better developing results.

It has been found, furthermore, that the wool cut plush fabric has a greatly to be desired useful life. The life of a typical wool cut plus fabric has been found, in some instances, to extend over the developing of 150,000 square feet of photolithographic plate surface. This is important, since it practically eliminates the high cost of the wiping cloths required in the hand operation of developing such plates.

The mechanical operation of the present developing head is obtained from a suitable source of power as a motor (not shown) connected to the drive shaft 57 located at one side of the frame of table 1. This power input to the drive shaft 57 may be seen in connection with Figs. 1 and 2. The drive shaft 57 is provided with a beveled gear 58 which meshes with a second beveled gear 59 fixed to a vertically directed shaft member 60 carrying at its upper end a bearing plate 61 provided with an eccentrically located drive pin 62. A cross shaft 63 is provided at one end with a bevel gear 64 meshing with the bevel gear 59 and having at its opposite end a bevel gear 65 which meshes with bevel gear 66 carried by a second vertically directed shaft 67 having a bearing plate 68 at its upper end carrying an eccentrically located pin 69. The cross bar 42 which supports the hollow head is provided with a bearing aperture 70 at its drive end and with a slotted bearing opening 71 at its opposite end. These bearing openings 70 and 71 are engaged respectively by the drive pins 62 and 69 carried by the respective bearing plates 61 and 68. It is obvious that rotation of the drive shaft 57 produces simultaneous rotation of the bearing plates and the pins thereon so that the cross bar 42 is caused to move in a circular orbit which produces both crosswise and longitudinal movement relative to the photolithographic plate being moved therebelow.

The hollow head 20 may be leveled or angularly adjusted with respect to the normal horizontal position of the photolithographic plate by means of the leveling screws 46, previously described. In Fig. 4, it will be observed that the leveling screws 46 contact the exposed surface of the blacking bars 51 and that by threading up or backing off the leveling screws at one longitudinal side or the other of the head, the head may be moved or angularly rocked relative to the guide portions 36 and 44 to change the position of its leading edge, thereby permitting the photolithographic plate to pass beneath the hollow head without striking a portion of the head or digging into the blanket B.

The head 20, furthermore, carries a photolithographic plate hold down arm which is shown at 73. This hold down arm comprises a longitudinal guide bar 74 having a beveled leading face 75 which is positioned to direct the leading edge of the photolithographic plate down and under the head 20. The bar 74 is pivotally mounted at the opposite ends of the head 20 by arm members 76 (Figs. 3 and 4) carried thereon by pivot elements 77 which cooperate with fixed stop elements 78 to limit the downward pivoting motion of the guide bar 74.

The hold down means 73, of course, may be pivoted upwardly and rearwardly to a position

out of the way when it is necessary to remove blanket B and replace it by a new blanket. The removal of the blanket B may be easily accomplished without disturbing the desired setting of the leveling screws 46 by threading the screws 39 to permit the head 20 to drop away from the leveling screws a sufficient distance so that the back bar 51 engaging the longitudinal edge of the blanket B may be lifted away to disengage the bar 50 from the stop pin 54 without striking the leveling screws.

The present invention has been described in connection with a preferred construction in which there is employed a pile fabric of wool cut plush.

However, it is obvious that changes may be made in the construction of the developing head and certain variations may be had in the characteristic of the pile fabric of wool cut plush without departing from the scope of the invention defined by the appended claims.

What I claim is:

1. In a photolithographic plate treating machine for removing excess non-printing ink from the plate, a panel to support the plates moved through the machine, a movable hollow body extending substantially the width of said plate supporting panel and having a perforated bottom face spaced from said panel, drive means relatively loosely connected with said body for moving the same in a circular orbit over said panel on which the plates move, a blanket carried on said body covering said bottom face, said blanket being of a character receptive to the printing ink and consisting of pile fabric of wool cut plush with a tightly woven warp and weft forming a firm ground texture, and conduit means connected with said body supplying a fluid at relatively low pressure thereto for flow through said perforated bottom face, the fluid escaping through the said blanket and simultaneously distending the blanket into a position yieldable to the thickness of the plate and erecting the filaments of the pile cut plush into gentle yielding contact with the plate and flushing away the excess of the non-printing ink contacted and loosened by the distended filaments, the pressure of said fluid distending said blanket causing said loosely connected body to assume a position relative to said drive means for controlling the pressure of contact of the filaments with the plate.

2. In a photolithographic plate treating machine, a supporting panel over which the exposed inked plates move during the developing treatment to remove excess non-printing ink, a hollow body extending substantially the width of said supporting panel and having an inlet for developing fluid and a large area bottom face with outlet ports therein, a conduit connected to said body inlet to conduct developing fluid thereto under relatively low pressure, a movable cross bar on the machine extending over said panel, power operated means on the machine connected with said cross bar for moving said cross bar in a circular orbit, cooperating members on said body and cross bar adjustably and loosely mounting said body spaced above said panel, and a blanket covering the bottom face area of said body, said blanket being of a character receptive to the printing ink and comprising a pile fabric of wool cut plush with a tightly woven warp and weft to form a firm ground texture, said fluid escape through said body outlet ports being resisted by said blanket with the pile filaments becoming distended and yieldingly held in touching relation with the plate being treated to dislodge the ex-

cess non-printing ink for removal by the flushing action of the fluid, the pressure of said fluid distending said blanket causing said loosely mounted body to assume a position for controlling the contact of the filaments with the plate.

3. The photolithographic plate treating machine set forth in claim 2, in which removable clamp means is provided to hold said blanket along opposite margins, said clamp means tightening said blanket over the bottom face of said body.

4. The photolithographic plate treating machine set forth in claim 2, in which cooperating clamping members hold said blanket along opposite margins, and pin elements in the upper surface of said body locate said clamping members with said blanket tightened over the bottom face of said body.

5. The photolithographic plate treating machine set forth in claim 2, in which plate hold down means is carried on said body, said means including a guide member located to guide the plates beneath said body for contact by the distended pile filaments of said blanket.
